(57) **CLAIM**

The ornamental design for a pom holder, substantially as shown and described.

DESCRIPTION

FIG. 1 is an isometric view showing the front, top and one side of my invention, as it would appear with a pom in place; FIG. 2 is a view similar to FIG. 1, showing the holder without the pom;

FIG. 3 is an elevation view of the front of my invention;

FIG. 4 is an elevation view of one side of my invention;

FIG. 5 is an elevation view of the rear of my invention;

FIG. 6 is an elevation view of the other side of my invention; and,

FIG. 7 is an elevation view of the bottom of my invention.

The pom illustrated in dot and dash in FIG. 1 and the word "indicia" do not constitute a part of the invention.
